Primary Examiner — Cynthia M. Chin

(74) Attorney, Agent, or Firm — Inskeep IP Group, Inc.

(57) **CLAIM**

The ornamental design for a toy brick, as shown and described.

DESCRIPTION

FIG. 1 is a front, right and top perspective view of a toy brick, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings illustrate portions of the toy brick that form no part of the claimed design.
